TABLE LAMP

Alfredo Martini, Via della Giardina, Monza, Italy, and
Roberto Coizet, Pizza Oberdan 4, Milan, Italy

Filed Oct. 19, 1970, Ser. No. 25,537

Term of patent 14 years

Int. Cl. D26—05

U.S. Cl. D48—20

FIG. 1 is a top plan view of a table lamp showing my new design, the lamp being fragmentarily shown for convenience of illustration;

FIG. 2 is a side elevational view thereof; and

FIG. 3 is a perspective view thereof on a reduced scale. The lamp is shaded to indicate translucency.

I claim:

The ornamental design for a table lamp, as shown and described.
